UNITED STATES PATENT OFFICE.

MATTHEW MONCASTER AND GEORGE HOLLINSHEAD, OF ROCHDALE, ENGLAND.

SELF-CLOSING OR SLEEPING DOLL'S EYES.

1,324,843.

Specification of Letters Patent.

Patented Dec. 16, 1919.

Application filed June 7, 1919. Serial No. 302,503.

To all whom it may concern:

Be it known that we, MATTHEW MONCASTER, of 67 Drake street, Rochdale, England, and GEORGE HOLLINSHEAD, of 5 Dunsterville Terrace, Rochdale, England, have invented certain new and useful Improvements in and Relating to Self-Closing or Sleeping Dolls' Eyes, of which the following is a specification.

10 This invention relates to an improved mechanism of self-closing, or sleeping dolls' eyes, whereby the self-closing action may be obtained with a more natural effect than with existing arrangements at present in use.

15 Most of the existing arrangements consist in constructing the eyes so that they roll bodily in sockets under the action of a balance weight, the appearance of the closing eyelid being obtained from a wax or other 20 coating on the eye itself.

According to this invention, the eyeballs instead of rolling are permanently fixed against rotation in the head of the doll, and thin movable lids are provided which are 25 adapted to be projected through slot apertures above the fixed eyeballs and sweep around the front thereof to mask the eyes when the doll's head is laid down. This may be effected by carrying the lids on a 30 weighted frame which is pivoted in a bracket or plate secured to the interior of the doll's head.

The invention is illustrated in the accompanying drawings, in which Figure 1. is a 35 vertical section through a doll's head showing the self-closing eyelid in the open position, Fig. 2, being a sectional view analogous to Fig. 1. showing the doll's head laid down and the eyelids closed. Fig. 3. is a perspective view of the construction of pivoted and 40 weighted frame for controlling the movement of the eyelids, Fig. 4. being a front view of the pivoted frame, and its bracket support, Fig. 5. being a rear view and Fig. 45 6. a side view.

In carrying out the invention a frame 1, the upper end of which is bent over and shaped to form two eyelids 2, is pivoted at 3 in a bracket 4 which is cemented or otherwise fixed in the doll's head 5. The parts 50 2 of the frame are curved and fashioned to represent eyelids and tinted as required, and these eyelids may be provided with lashes 6. The rear of the frame 1 is fitted with a 55 weight 7 which is supported from the tail of

the frame by wires 8. The usual cork stop 9 may be provided to deaden the impact of the weight 7, and in order to enable the bracket 4 to be more securely held in the doll's head, and to give facility in fixing it 60 therein, it may be provided with wings 10 or the like projections which are adapted to be embedded in the cement fixing. Curved slot apertures 11 are formed above the eyeball 12 through which the eyelid parts 2 65 may project to sweep around the front of the eyeballs 12 when the doll's head is laid down as shown in Fig. 2.

In fitting the mechanism, in order to form the curved slot apertures 11 through which 70 the movable lids are adapted to project two spoon shaped elements are provided which rest against the eyeballs so that the tips of the spoon elements project into the interior of the doll's head. The cement 13 by means 75 of which the eyeballs 12 are then permanently secured in the doll's head is run around the eyeballs and inwardly projecting tips of the spoon elements and when allowed to set, or before setting, on withdrawal of 80 the spoon elements curved slot apertures will be thus left through which the lids 2 may move, the bracket plate 4 and weighted pivotal frame 1 being fitted simultaneously 85 with the eyeballs 12 or subsequently as desired.

The position of the bracket 4 with reference to the eyes is preferably that shown in Figs. 1 and 2, the inner corner 4^a of the bracket plate engaging beneath the inwardly projecting ridge on the eyeballs 12, the bracket 4 thus acting as a rear support for the eyeballs and preventing them 90 from being pushed in from the outside.

As mentioned above, the eyelids may be 95 fitted with lashes and the tops of the lids may be treated with a wax coating 14, which wax coating besides giving a more natural appearance to the lids also acts as a lubricant enabling the lids more readily to pass 100 in and out of the curved slots 11. The eye lashes 6 may be put on in any suitable manner. The pivoted frame 1 and the bracket 4 may be very economically manufactured 105 from light sheet metal stampings as shown.

We claim:

In a doll, a head including eyes and having slots formed over the eyes, a bracket including a front wall and side walls, wing members formed integral with the side walls 110

of the bracket and providing means for securing the bracket within the head, a frame having curved portions operating through the slotted portions, said frame having a pivotal connection with the bracket, and a weight connected to the frame, whereby movement of the weight causes a relative movement of the curved portion.

In testimony where we affix our signatures in presence of two witnesses.

MATTHEW MONCASTER.
GEORGE HOLLINSHEAD.
